(57) **CLAIM**

The ornamental design for a golf club head, as shown and described.

DESCRIPTION

FIG. 1 is a rear and toe side perspective view of a golf club head.

FIG. 2 is a rear and heel side perspective view of the golf club head of FIG. 1.

FIG. 3 is a front elevation view of the golf club head of FIG. 1.

FIG. 4 is a rear elevation view of the golf club head of FIG. 1.

FIG. 5 is a side elevation view of a toe side of the golf club head of FIG. 1.

FIG. 6 is a side elevation view of a heel side of the golf club head of FIG. 1.

FIG. 7 is a top plan view of the golf club head of FIG. 1.

FIG. 8 is a bottom plan view of the golf club head of FIG. 1.

FIG. 9 is a cross-sectional view of the golf club head taken along line 9-9 of FIG. 4; and,

FIG. 10 is a cross-sectional view of the golf club head taken along line 10-10 of FIG. 4.

The broken lines in the drawings are for purposes of illustrating environmental structure as well as portions of the design that form no part of the present claimed design. The dash-dot-dash broken lines in the drawings represent unclaimed boundaries and form no part of the present claimed design.

1 Claim, 6 Drawing Sheets
